(57) CLAIM

The ornamental design for a wheeled cart, as shown and described.

DESCRIPTION

FIG. 1 is a front top right isometric view of the wheeled cart of the present invention;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a top right rear isometric view thereof;

FIG. 9 is a bottom right front isometric view thereof; and,

FIG. 10 is a bottom right rear view thereof.

The portions of the wheeled cart that are illustrated in broken lines form no part of the claim for the wheeled cart.
